CARTRIDGE POSITIONING MACHINE

Edward Almond Jackson, Doncaster, England

Application April 2, 1942, Serial No. 437,329
In Great Britain November 14, 1941

12 Claims. (Cl. 86—48)

This invention consists in improvements in or relating to cartridge positioning machines particularly designed to effect an accurate positioning of cartridges in a belt of the metal link or jointed type as is requisite in ammunition belts for machine guns, or any gun in which successive rounds are fed to the machine by means of a travelling belt. It is unnecessary to stress the need for accurate positioning of the cartridges in the belt so that all of the cartridges are uniformly held therein as it is well known that, particularly in guns from which a rapid fire is to take place, the passage of a belt in which the cartridges are not uniformly positioned relatively to the edges of the belt often leads to jamming and demobilisation of the gun.

The present invention is applied to a positioning machine of the kind comprising in combination a revolving tappet block or carrier containing a plurality of axially movable tappets which are rotated by the block in synchronism with cartridges that have been inserted in a belt and are fed in front of the tappets across the axis of rotation of the tappet block, a tappet cam for actuating the tappets so that each cartridge as it travels through the machine will be engaged with and adjusted in its position in the belt by movement of a tappet, and a belt feeding and locating device which traverses the belt of cartridges and locates the belt itself relatively to the tappet cam.

Hereinafter and in the appended claims a machine having this combination of parts will be referred to as "a cartridge belt positioning of the type specified."

One such machine has been described in prior British specification No. 533,424 and an object of the present invention is to provide improvements in a machine of this nature.

According to the present invention a cartridge positioning machine comprises in combination a revoluble tappet block, cartridge-belt traversing and locating means to traverse the belt relatively to the tappet block in a direction transverse to the axis thereof, a plurality of cartridge positioning tappets carried by the tappet block and spaced apart angularly around the axis thereof, each of which tappets is formed with an internal cavity, a spring in each tappet cavity compressible between an end thereof and an abutment on the tappet block and serving to urge the tappet resiliently in the direction of the belt as it is traversed past the tappet block, spring-engaging abutments in the tappet block and a drive-coupling between the latter means and the tappet

block whereby the tappets are brought successively into operative position synchronously with the traverse of the belt in order successively to engage and position cartridges located in the belt.

Preferably, the abutments carried by the tappet block comprises pins extending into the interior of the tappet, and each tappet is provided with an axial slot into or through which the pin passes and which permits axial movement of the tappet relatively to the pin and preferably serves as the means to prevent rotation of the tappet about its axis.

In order that the invention may be more clearly understood one preferred construction will now be described with the aid of the accompanying drawings, in which—

Figure 1 is a plan of the main portions of a cartridge belt filling machine according to one form of the invention;

Figure 2 is a section on the line 2—2 of Figure 1, looking in the direction of the arrows;

Figure 3 is a section on the line 3—3 of Figure 1, looking in the direction of the arrows;

Figure 4 is a section on the line 4—4 of Figure 1, looking in the direction of the arrows;

Figure 5 shows on an enlarged scale a portion of the mechanism shown in Figure 1 with some of the cartridges and a portion of the cartridge belt shown in position; and

Figure 6 is a section also similar to Figure 2 of a still further modification of the invention.

Like reference numerals indicate like parts in the several figures of the drawings.

In the construction shown in Figures 1 to 5, the cartridge belt and cartridges have been omitted, for the sake of clearness, from Figures 1 to 4. On a base 10 two end standards 11 and 12 are provided for supporting two portions 13 and 14 of a divided main driving shaft. Mounted on the portion 13 and keyed to that shaft by splines 15 is a tappet block 16 providing bearings for axially movable tappets 17 spaced equidistantly around the axis of the tappet block. A profile cam or swash plate 18 is received in the standard 11 so as to be non-rotatable but axially movable therein and, for this purpose, is slidable on two dowel pins 118 which are fixed in standard 11. The cam is adjustable as to its axial position by means of a screwed sleeve 19 which is retained in its position of adjustment by means of a lock-nut 20. The cam 18 has a sleeve-like extension 21 affording a bearing for the left-hand end of shaft 13 and is itself screwthreaded at its outer end to receive a locking ring 22 which is clamped in position by a setscrew 23 to ensure

that the cam 18 is adjustable by the screwed sleeve 19 and will not be displaced axially from that position of adjustment. The shaft 13 has a flange 24 between which and an opposed face of a recess in cam 18 is a ball thrust bearing 25 and the flange 24 is held up against this bearing by means of a collar 26 secured by grub-screw 27. Between the collar 26 and a clamping nut 28 a crank handle 29 is secured to the shaft.

The other shaft portion 14 has a bearing at one end in standard 12 and in the other end it is in splined engagement at 30 with the tappet block 16 so that shaft 14 is driven from shaft 13 through the medium of the tappet block but the latter is capable of adjustment axially relatively to shaft 14. On the latter is mounted to rotate with it a cartridge spacing wheel 31 and the toothed abutment member 32 which engages and positions the edge of the cartridge belt and all the parts so far described are similar in their main essentials to the corresponding parts described in prior British specification No. 533,424.

In the present construction, however, each of the tappets 17 is formed with an axial recess in which is received a compression spring 33, one end of which engages the end of the recess in the tappet and the other end of which abuts against a pin 34 which is screwthreaded radially into the tappet block 16 and passes completely through an axial slot 35 formed in the tappet itself. Thus while the tappet can slide axially on pin 34 the latter prevents rotation of the tappet about its own axis. The operative head of the tappet may be cylindrical as shown in Figure 6, but in order to reduce or enlarge the effective pitch circle of the tappets to accommodate either smaller or larger ammunition respectively without unduly reducing or unduly enlarging the tappet size, the tappet head may be either inturned or out-turned respectively. In the present example, it is shown as inturned so that the part of the tappet head which will engage the cartridge lies within the radius of a circle on which the longitudinal axis of the tappets will lie. The operative portion of the tappet head is shown at 36 and it will be observed that the longitudinal axis of the tappet is radially beyond this effective head portion.

In order to insert the springs 33 in position the tappet is bored longitudinally from the outer face of the tappet head to the base of the recess so that the springs can be inserted and pins 34 then passed through slots 35 to be screwed in position to retain springs 33 in place.

According to another feature of the invention the feed and outlet boards 37 and 38 respectively are hinged at 39 and 40 respectively to the base 10 so that they can be adjusted to any suitable angle of inclination with respect to the horizontal guide platforms 41 from which the belt and cartridges pass to the spacing wheel 31 and sprocket 42 which is associated with the spacing wheel in the feeding of the belt through the machine and to the exit platform 43 from those feeding devices. Above platforms 41 and 43 there is now provided a cover comprising two fixed parts 44 and 45 bridged by a hinged cover 46. At one end the cover can turn about a fixed pin 47 and can be secured in place by a removable pin 48, both pins passing, as shown in Figure 1, through ears constituting extensions from the fixed covers 44 and 45 and through the requisite holes in the ends of cover 46 which is located between the ears.

As in the case of the construction described

in the prior British specification aforementioned, the belt is guided by a fixed guide plate 49 as it travels from left to right in Figure 3 into and through the machine.

Briefly described, it will be understood that as the belt with the cartridges quickly and somewhat roughly placed in position therein passes through the machine, it travels up the feed board 37 onto the horizontal platform 41 and thus over the feed wheel and feed sprocket 31 and 42, and synchronously with movement of the belt the tappet block is rotated so that each cartridge is engaged by a separately actuated tappet the movement of which is controlled by means of the tappet cam 18. Rotation of the tappet block and the cartridge belt feeding devices is effected by rotation of crank handle 29 and the distance to which the cartridges are pushed into the belt is determined by the adjustment of the position of the tappet cam 18 relatively to the toothed abutment 32. It is the latter which holds the edge of the cartridge belt during the adjustment of the cartridges therein. This is shown clearly in Figure 5.

25 In the form illustrated in Figure 6 the tappets are in this case again internally sprung but instead of being formed with offset heads 36 they are now formed with plain cylindrical heads 136. In this construction, however, which is designed 30 to deal with relatively heavy ammunition, the driving shaft is rotated by handle 29 through reduction gearing contained in a gear box designated generally by the reference 53. The reduction gearing comprises gear 54 to which the crank 35 handle 29 is secured, an intermeshing gear 55 mounted to rotate on a stub axle 56 carried in the gear box, a smaller gear 57 integral with gear 55 and finally a gear 58 which intermeshes with gear 57 and is splined onto the end of shaft 13. 40 and secured thereto between a collar 59 on sheath 13 and a clamping castellated nut 69 held in its clamping position by a split pin 61. Hinged feed and outlet boards and a hinged cover over the feed wheels is provided as before but in this case 45 it will not be convenient to adjust the axial position of the tappet cam relatively to the feeding devices and therefore it is the latter that are adjusted simultaneously by means of a screwthreaded sleeve 62 received in standard 12 and locked in positions of adjustment by means of lock nuts 63 and 64. A thrust ball bearing 65 is located between the end of sleeve 62 and a part 66 forming an extension of and beyond the toothed abutment 32.

I claim:

1. A cartridge positioning machine comprising in combination a revoluble tappet block, cartridge-belt traversing and locating means to traverse the belt relatively to the tappet block in a direction transverse to the axis thereof, a plurality of cartridge positioning tappets carried by the tappet block and spaced apart angularly around the axis thereof, each of which tappets is formed with an internal cavity, a spring in each tappet cavity compressible between an end thereof and an abutment on the tappet block and serving to urge the tappet resiliently in the direction of the belt as it is traversed past the tappet block, spring-engaging abutments in the tappet block and a drive-coupling between the latter means and the tappet block whereby the tappets are brought successively into operative position synchronously with the traverse of the belt in order successively to engage and position cartridges located in the belt.

2. In a cartridge-belt-filling machine the combination according to claim 1 together with means to prevent rotation of the tappet about its axis.

3. In a cartridge-belt-filling machine the combination according to claim 1 in which the abutment carried by the tappet block to engage one end of a tappet spring comprises a pin extending into the interior of the tappet and in which the tappet is provided with an axial slot within which the pin is engaged and which permits axial movement of the tappet relatively to the pin.

4. In a cartridge-belt-filling machine the combination according to claim 1 in which each tappet is provided with diametrically opposed axial slots in opposite walls of the cavitated portion of the tappet and in which the abutment carried by the tappet block to engage one end of the spring comprises a pin which extends through both slots in the tappet walls.

5. In a cartridge-belt-filling machine the combination according to claim 1 wherein that end of the tappet that is to engage a cartridge is offset from the axis of the tappet.

6. In a cartridge-belt-filling machine the combination according to claim 1 having feeding and outlet boards for guiding the belt into and out from the machine, the lengths of which boards extend transversely to the axis of the tappet block and one at least of which is hinged for the purpose of adjusting its inclination.

7. In a cartridge-belt-filling machine the combination according to claim 1 having feeding and outlet boards for guiding the belt into and

out from the machine, the lengths of which boards extend transversely to the axis of the tappet block and each of which boards is hinged for the purpose of adjusting its inclination.

5. 8. The combination according to claim 1 together with an upper cover provided above the belt-feeding and locating means.

9. The combination according to claim 1 which together with an upper cover is provided above the belt feeding and locating means and extends on both sides thereof.

10. The combination according to claim 1 together with an upper cover provided above the belt-feeding and locating means, said cover having a central portion which is movable to give access to the belt-feeding and locating means.

11. The combination according to claim 1 and in addition a main driving shaft for rotating the tappet block and belt-feeding means, and 20 actuating handle for turning the shaft, and reduction gearing constituting the driving connection between the handle and the shaft.

12. The combination according to claim 1 and in addition a main driving shaft for rotating the tappet block and belt-feeding means, an actuating handle for turning the shaft, reduction gearing constituting the driving connection between the handle and the shaft, and means also to adjust the axial position of the belt-feeding and 25 locating means towards and away from the tappet cam.

EDWARD ALMOND JACKSON.
